UNITED STATES PATENT OFFICE

GEORGE HENRY WHEARY, OF RACINE, WISCONSIN, ASSIGNOR TO WHEARY TRUNK COMPANY, OF RACINE, WISCONSIN, A CORPORATION OF WISCONSIN

HAND LUGGAGE

Application filed December 2, 1929. Serial No. 411,091.

This invention relates to certain new and useful improvements in hand luggage of the general type illustrated in the copending application of Benjamin M. Hamlin, assigned to the Wheary Trunk Co., Serial No. 406,395, wherein provision is made for carrying a complete man's suit in a case of conventional size without wrinkling.

An object of this invention resides in the provision of an improved case having an internal cover for the lid with means for holding a man's suit in the space between said cover and the lid walls.

A more specific object of this invention resides in the provision of an improved case, the lid of which is provided with an internal cover having a bar or frame member co-operating with a hanger whereby garments may be secured over hangers and then medially draped over the bar to be held in neat form against wrinkling.

A further object of this invention resides in the provision of an improved case of the character described which is capable of carrying a complete man's suit without wrinkling and which may be readily converted into a conventional plain case.

And a still further object of this invention resides in the provision of an improved case of the character described which readily lends itself to provision of means for handling more than one suit or garment without unduly increasing the over-all depth of the case lid or cover.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated several complete examples of the physical embodiment of my invention constructed according to the best modes I have so far devised for the practical application of the principles thereof, and in which:

Figure 1 is a fragmentary view of a man's case embodying my invention, the lid being in open position and the internal cover and garment hanging means in the position occupied as a garment is being placed therein, portions of the lid being broken away to illustrate structural details;

Figure 2 is a transverse, sectional view through the lid and rearward portion of the main section with the lid in open position, said view being taken through Figure 1 on the plane of the line 2-2;

Figure 3 is a perspective view of one end of the garment supporting member or bar over which the garments are draped and the retainer therefor;

Figure 4 is a view similar to Figure 2 of a modified structure having provision for handling more than one suit;

Figure 5 is a fragmentary perspective view of the hanger keeper illustrated in Figure 4 for handling two hangers;

Figure 6 is a view similar to Figure 1 of a further modified form of my invention;

Figure 7 is a view similar to Figure 2 taken through Figure 6 on the plane of the line 7-7;

Figure 8 is a fragmentary perspective view of the fastener carried by the hanger illustrated in Figure 6;

Figure 9 is a view similar to Figure 1 of a still further modification of my invention;

Figure 10 is a view similar to Figure 2 taken through Figure 9 on the plane of the line 10-10; and

Figure 11 is a fragmentary detail view of the means removably securing the cover in the lid, said view being taken through Figure 9 on the plane of the line 11-11.

Referring now more particularly to the accompanying drawings, in which like numerals designate like parts throughout the several views, 5 represents the main section of a luggage carrier of the hand case type having a lid 6 hingedly connected therewith along one marginal edge, as at 7. As is customary, the case is provided with a conventional handle 8 and locking devices 9.

The main section of the case may be subdivided according to the particular uses to

which the case is to be applied and preferably has a stepped shoulder 10 about its marginal edge over which the lid telescopes to insure a strong and substantially dust-proof juncture between the lid and section. The lid has depth but preferably less than that of the main section and an internal cover 11 is hinged to the lid bottom wall 12 along its marginal edge, as at 13, the cover being secured in position over the lid by suitable fastening means 14 and its free end portion opposite the hinged end 13 is maintained spaced from the lid outer wall by bracket members 15, to be later described.

As illustrated in the drawings, the internal cover 11 is movable to a position over the main case when the lid is open and a garment supporting member or bar 16 is securable between the brackets 15 to cooperate with a garment hanger 17 and neatly support a complete man's suit against wrinkling. The bar 16 preferably has a covering or cushion thereover to prevent creasing of the garment draped thereover and its ends are provided with metal caps 18 having end projections or bosses 19 preferably of rectangular shape which engage in correspondingly shaped apertures 20 in the bracket members. The apertures 20 are preferably over-size to permit limited movement of the bosses 19 longitudinally with respect to the bracket members.

The hanger 17 is preferably of the conventional man's type having a top bar 21 of approximately inverted V shape to conform with the shoulders of a coat and a connecting bottom or horizontal bar 22 over which trousers are adapted to be draped. A projection or boss 23 extends laterally from the apex of the top bar 21 to mount an approximately T shaped head or fastener 24 adapted for engagement in the T shaped slot 25 of a keeper 26 fixed to the side wall 12 of the lid. The keeper 26 is substantially channel shape and the small portion of the T slot 25 extends into its forward vertical flange or wall 27 to permit movement of the hanger to an angular position with respect to the lid, or in other words, allow the hanger with a suit thereon to assume a horizontal position when the cover is open to facilitate proper arrangement of the suit, as best illustrated in Figure 1.

The hanger is further provided adjacent the fastener with a pivoted hook 28 to enable its use apart from the case, as will be readily apparent.

In arranging a suit in the case, the trousers T are draped over the horizontal bar 22 of the hanger, and the coat and vest, C and V, respectively, next placed over the top bar 21 in the conventional manner. The cover 11 is then swung to its position illustrated in Figure 1, and the fastener 24 engaged in its keeper so that the suit rests on

the cover as illustrated. The garment is then straightened out so that all folds are along normal lines and bar 16 then secured in place and that portion of the suit extending therebeyond folded thereover onto the portion of the suit on the cover 11 and then straightened out to assure elimination of unnecessary folds.

The cover 11 with the suit thus placed is swung over the lid 6 and the fastening means 14 secured in place, the garment being held against shifting by its compression between the cover and lid.

If desired, each bracket member may be provided with more than one aperture 20 so that heavy or light suits may be readily accommodated although it is unnecessary to hold the suit between the bar and the cover by pressure, the garment being held against shifting by its compression between the cover 11 and the lid 6, as before described. The outer ends of the bracket members are preferably directed laterally, as at 29, to engage against the rear of the lid 6 and form a stop.

More than one suit may be carried by increasing the over-all depth of the lid and enlarging the bracket members 15 accordingly so that two staggered series of openings 20 are formed in each one in the manner illustrated in Figure 4. In this form, the keeper 26 has its front wall 27 stepped, as at 30, and the outer stepped portion provided with a T shaped opening 31.

The manner of securing the garments in the case in the form illustrated in Figures 4 and 5 is identical with that previously described, the outer-most hanger and the suit carried thereby being first secured in place and then the inner-most hanger and its garment.

In the structure illustrated in Figures 6, 7, and 8, the T shaped fasteners 24 of the hanger 17 are replaced by a fastener 32 provided with a key-hole slot 33 in its end portion 34 extended beyond the hanger proper to receive a stud or post 35 carried by the cover 11. The stud or post 35 has a head or enlargement 36 on its outer end of a diameter to pass through the large end of the key hole slot, but of less diameter than the small end thereof. The bracket members 15 in this form of my invention are preferably of arcuate shape and the series of apertures 20 therein are stepped to facilitate the securing of more than one garment in the case.

In Figures 9, 10, and 11, the cover 11 is illustrated as being removably hinged in the lid by pintles or pivots 37 projected laterally from the innermost corners thereof for engagement in apertures 38 in corner pieces 39 secured in the innermost corners of the lid. The pintles 37 are urged outwardly by springs 40 at all times and are provided with finger engaging members 41 for convenience

in retracting the same for removal from the cover.

If desired, a second internal cover 42 may be provided which is likewise removably secured in the lid by pintles or pivots 37. In this form of my invention, the garment supporting members or bars 16 are received in brackets similar in construction to those illustrated in Figure 1, the brackets providing positive stops maintaining the cover in proper spaced relation in the lid.

It will be readily apparent that in this form of my invention either of the covers 11 and 42 may be removed and the case utilized without the means for carrying a suit. If desired, the cover 11 may be replaced by a plain one such as employed in the conventional type of men's Gladstone bags.

From the foregoing description taken in connection with the accompanying drawings, it will be readily apparent to those skilled in the art to which an invention of the character described appertains, that I have provided a novel and improved man's case having provision for packing a man's suit consisting of trousers, coat, and vest, and holding the same against wrinkling as the case is handled.

What I claim as my invention is:

1. A luggage carrier including a main section and a lid hingedly connected therewith, an internal cover for the lid, a garment supporting member carried by the cover, a garment hanger, and means for mounting the garment hanger near the hinged connection of the lid and main section, said hanger being adapted to have a garment draped thereover and the garment then extended outwardly over the internal cover and about the supporting member carried thereby.

2. A luggage carrier including a main section and a lid hingedly connected therewith, an internal cover for the lid, a garment supporting member removably carried by the cover, a garment hanger and means for mounting the garment hanger between the cover and lid, and near the hinged connection of the main section and the lid, whereby a garment draped over the hanger may be extended outwardly over the internal cover and about the supporting member carried thereby.

3. A luggage carrier including a main section and a lid hingedly connected therewith, an internal cover for the lid, a garment supporting member carried by the cover, a garment hanger, and means for readily removably mounting the garment hanger between the cover and lid and near the hinged connection of the main section and the lid, said hanger being adapted to have a garment draped thereover and the garment then extended over the internal cover and about the supporting member carried thereby.

4. A luggage carrier including a main section and a lid hingedly connected therewith,

an internal cover for the lid, a garment supporting member carried by the cover, a garment hanger, means for mounting the garment hanger between the cover and lid near the hinged connection of the main section and lid, said hanger being adapted to have a garment draped thereover and the garment then extended over the internal cover and about the supporting member carried thereby, and means securing the cover in the lid whereby the same is carried thereby in its opening and closing movements.

5. A luggage carrier including a main section and a lid therefor having depth, an internal cover for the lid, bracket members secured to the cover adjacent its outermost corners, a garment supporting member mounted between the bracket members, a garment hanger, and means securing the hanger between the cover and the lid, said hanger being adapted to have a garment draped thereover and the garment then extended over the internal cover and about the member carried thereby.

6. A luggage carrier including a main section and a lid therefor having depth, an internal cover for the lid, bracket members secured to the cover inner face adjacent its outermost corners, a garment supporting member removably secured between the bracket members, a garment hanger, means securing the hanger between the cover and the lid, said hanger being adapted to have a garment draped thereover and the garment then extended over the internal cover and about the member carried thereby, and stops on the outer ends of the bracket members engageable with the lid back wall to maintain the cover spaced therefrom.

7. A luggage carrier including a main section and a lid therefor having depth, an internal cover for the lid, bracket members secured to the cover inner surface adjacent its outermost corners, a garment supporting member removably mounted between the bracket members, a garment hanger, means securing the hanger between the cover and the lid, said hanger being adapted to have a garment draped thereover and the garment then extended over the internal cover and about the member carried thereby, and stops on the outer ends of the bracket members engageable with the lid back wall to maintain the cover spaced therefrom, said garment supporting member having a limited movement in the bracket members toward and from the cover member to accommodate garments of different thicknesses.

8. A luggage carrier including a main section and a lid having depth, means hingedly connecting the main section and lid, a pivotally mounted internal cover for the lid, means for securing the cover over the lid, there being a garment receiving space between the cover and lid, a garment support

ing member carried by the cover, a garment hanger having a substantially inverted V shaped top bar and a horizontal bar connecting the ends of the top bar, whereby a pair of trousers may be draped over the horizontal bar and a coat and vest draped about the top bar, and means pivotally securing the garment hanger to the lid adjacent its hinged connection with the main section, whereby a man's suit carried by said hanger may be extended along the internal cover and folded on itself about the member carried by the cover.

9. A luggage carrier including a main section and a lid therefor, an internal cover for the lid, a garment supporting member carried by the cover adjacent its outer marginal edge, a garment hanger, and means securing the garment hanger to the cover adjacent its inner marginal edge, said hanger being adapted to have a garment draped thereover and the garment then extended over the internal cover and about the member carried thereby.

10. A luggage carrier including a main section and a lid hingedly connected therewith, said lid and main section being hingedly connected along one marginal edge, an internal cover for the lid, means hingedly mounting the cover for movement over the lid, said hinged means being located juxtapose the hinged connection between the lid and main section, a garment supporting member carried by the cover near its outer free end, a garment hanger, means for mounting the garment hanger for movement with and independently of the internal cover about the axis adjacent the hinged mounting of the cover between the cover and lid, said hanger being adapted to have a garment draped thereover and the garment extended over the internal cover and about the supporting member carried thereby.

11. A luggage carrier including a main section and a lid therefor, said lid and main cover being hingedly connected along one marginal edge, an internal cover for the lid, means hingedly mounting the cover for movement over the lid, means removably hingedly securing the cover to the lid adjacent its hinged connection with the main section, said hinged securing means being located juxtapose the hinged connection between the lid and main section, a garment supporting member carried by the cover near its outer free end, a garment hanger, and means securing the garment hanger between the cover and lid and near the hinged securing means for the cover, said hanger being adapted to have a garment draped thereover and the garment extended over the internal cover and about the supporting member carried thereby.

12. A luggage carrier including a main section and a lid hingedly connected there-

with, an internal cover for the lid, means securing the cover over the lid, a mounting post carried by the cover adjacent its hinged connection with the main section extending into the lid, a garment hanger adapted to be hung from said mounting post, and a garment supporting member carried by the cover near its end opposite said mounting post, said hanger being adapted to have a garment draped thereover and the garment then extended over the internal cover and about the member carried thereby.

13. In a hand luggage case including a main section and a lid hingedly connected therewith, an internal cover for the lid, a garment supporting member, means for mounting the garment supporting member from the internal cover, said means being engageable with the lid to maintain the cover spaced therefrom, a garment hanger and means mounting the garment hanger between the cover and the lid near the hinged connection of the main section and lid whereby a garment draped over the hanger may be extended outwardly over the internal cover and about the garment supporting member carried thereby.

14. In a hand luggage case including hingedly connected sections, an internal cover member, means mounting said cover member for movement into and out of alignment with either section when the case is open, rigid garment supporting members, means at one side of the cover for mounting the garment supporting members from the outer free end thereof whereby said garment supporting members are disposed in the space between the cover and one of the sections when the cover is aligned therewith, garment hangers, and means for mounting the garment hangers in said space between the cover and said section in offset relationship to reduce the overall thickness of the garments draped over the hangers, the garments extending outwardly from the hangers over the internal cover to be folded over the garment supports at the outer free end thereof.

15. In a hand luggage case including hingedly connected complementary sections, a plurality of internal cover members hingedly mounted in one section for swinging movement to and from alignment with either section when the case is open, said internal cover members dividing the depth of the section in which they are mounted into separate compartments, garment hangers adapted to have garments draped thereover, means for mounting said garment hangers in the separate compartments near the hinged connection of the sections, a garment supporting bar for each compartment, and means for mounting the garment supporting bars from the internal covers near the outer free ends of the covers, garments draped over the

hanglers being extended outwardly over the internal covers to be folded over the garment supporting bars, and the means for mounting the garment supporting bars being of a width substantially equal to the width of the compartments to maintain the internal covers properly spaced from each other and from the section in which they are mounted.

16. A hand luggage carrier comprising hingedly connected sections, an internal cover for one of the sections, a garment supporting member carried by the internal cover, a garment hanger, and means for mounting the garment hanger near the hinged connection of the sections, said hanger being adapted to have a garment draped thereover and the garment then extended outwardly over the internal cover and disposed about the supporting member carried thereby.

17. A hand luggage carrier comprising hingedly connected sections, an internal cover for one of the sections hingedly mounted for swinging movement about an axis adjacent the hinged connection of the sections, a garment supporting member carried by the internal cover at its outer free end portion, a garment hanger, and means for mounting the garment hanger near the hinged connection of the sections, said hanger being adapted to have a garment draped thereover and the garment extended outwardly over the internal cover and engaged about the supporting member carried thereby.

18. In testimony whereof I have hereunto affixed my signature.

GEORGE HENRY WHEARY.
